APPARATUS FOR GRINDING A DRILL

Jiro Hamai, Shinagawa-ku, Tokyo-to, Japan

Application February 7, 1956, Serial No. 564,065

4 Claims. (Cl. 51—72)

This invention relates to apparatus for grinding twist drills and more particularly to an apparatus wherein the grinding of the point of a drill for the purpose of thinning the point, i. e. for the purpose of reducing the width of the chisel edge or web is facilitated.

It is well known that the operation of properly sharpening a twist drill, if carried out by an operator holding the drill only in his hands, requires great skill if improper forming of the various critical angles and dimensions required in the point area is to be avoided.

It is therefore a main object of this invention to provide for an apparatus for grinding twist drills in which the drill is mechanically supported during the grinding operation, and particularly during that operation which is designed to thin the point.

With above object in view, the apparatus according to the invention mainly consists, in combination, of a rotary grinding wheel having a rim with a flat circular surface and a beveled surface, said surfaces forming a circular edge; a base carrying said grinding wheel for rotation around a fixed axis; a turnable support member having an edge portion and being mounted in said base for turning movement in a plane perpendicular to said axis and in close proximity to said flat circular surface of said grinding wheel from a position in which said edge portion projects beyond said circular edge of said grinding wheel at least to a position in which a point of said edge portion substantially coincides with said circular edge of said grinding wheel; and spring means interposed between said base and said turnable support member for resiliently counteracting said movement of said turnable support member towards said axis, so that a twist drill held against the edge of the grinding wheel is resiliently supported by said edge portion of said movable support member engaging a flank of a flute of the drill near the tip thereof.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing in which:

Fig. 1 is a front view of an apparatus according to the invention;

Fig. 2 is a side view, partly in section, thereof, the section being taken along line B—B of Fig. 1;

Figs. 3 and 4 are cross-sectional fragmentary plan views along line A—A of Fig. 1, the former showing the drill as seen in axial direction thereof, and the latter showing the drill in side view in the position for grinding its cutting edges; and

Figs. 5, 6 and 6a illustrate various phases of the grinding operation for thinning the point.

Referring to the drawing, 1 is a grinding wheel mounted on a shaft 5 for rotation about the axis thereof and 2 is the beveled grinding surface forming together with a flat

2

rear surface 2a the circumferential edge of said wheel. The inclination of the beveled grinding surface 2 against said axis corresponds to that of the edge 4 of the drill 3 against its axis. The gears 6, 7, 8 and 9 are provided for driving the wheel 1. The drive shaft 10 of the last gear 9 carries a crank 11. A motor may be used in lieu of the crank. A flat movable support member 12 is mounted turnable about the center line of pivot points 16 and 16' supporting the axle 15 of the support member 12.

5 10 In all positions of the turnable support member 12 one face thereof remains in close proximity and parallel with the flat rear surface 2a of the grinding wheel 1. The movement of the upper end of the supporting member 12 in direction of arrow Z is counteracted by a spring 13 attached to the lower end of the member 12 and to a member of the base 19. A stop pin 14 limits this movement. The brackets 17 and 18 mounted on the base 19 carry the above mentioned components of the apparatus and are both inclined in the same direction.

15 20 In operating the apparatus, the crank 11 is rotated so as to put the gear wheels 9, 8, 7 and 6 in motion and to thus rotate the grinding wheel 1.

25 During such rotation of the grinding wheel, the drill edge 4 may be ground by bringing the same into contact with the beveled grinding surface 2 whereby the drill edge 4 is ground at the proper clearance angle if supported on a member 4a (Fig. 2) or held horizontally, the inclination of the brackets 17 and 18 and accordingly of the axis of the shaft 5 of the wheel 1 automatically determining the clearance angle. In this grinding operation not only the cutting edges of the drill 3 are sharpened but also the chisel edge 20 is formed.

30 In many cases it is desirable to thin the drill point which means to give the width of the chisel edge, i.e. the outermost end portion of the web between the opposite flutes of the drill, a suitable dimension which is less than the thickness of the web at that point. In order to carry out this operation, the end portion of the drill 3 is held with the flank 3a of one flute near the tip of the

35 40 drill against the outer surface of the support member 12 as is shown in Figs. 3 and 5 while the particular portion of the support member 12 is in the position shown in Figs. 1 and 4 where that particular edge portion of member 12 somewhat projects beyond the cutting edge of the wheel 1. If now some pressure is exerted on the drill 3 so as to move the engaged edge portion of the member 12, against the action of spring 13, in the direction of arrow Z, then the drill 3 steadied by the member 12 will move together with member 12 into a position as

45 50 illustrated in Fig. 3 in which the outer edge portion of the member 12 substantially coincides with the cutting edge of the wheel 1. It is clear that until then the wheel was prevented from touching and cutting the drill. If now further pressure is applied to the drill 3 so that it moves together with member 12 further in direction of arrow Z then the position shown in Fig. 6a will be reached so that the cutting edge of the wheel 1 will grind a notch into the web of the drill so as to reduce the width of the chisel edge 20 to the extent desired, depending upon to what extent the last mentioned movement is continued.

55 60 Some types of twist drills are produced with a web which gradually increases from the tip towards the shank for the purpose of greater rigidity. As during use and repeated resharpening of the drill the latter grows shorter, the thickness of the web at the tip comparatively increases. This is illustrated in Fig. 6 where the desirable depth or shape of the flute is indicated by 3' while the actual depth is indicated at 3". It can be seen that a deepening of the flute in the area near the point can also be performed by the apparatus of the invention in the manner generally described above except that after the

edge portion 3''' has been produced in the manner illustrated by Fig. 6a, the drill can be moved freehand so that the material between the curves 3' and 3''' is removed. Also in this case the member 12 will prevent any undesired grinding along the edges 3a and 3'''.

It will be understood that each of the elements described above, or two or more together, may also find a useful application in other types of grinding apparatus differing from the type described above.

While the invention has been illustrated and described as embodied in grinding apparatus for sharpening twist drills, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In an apparatus for grinding twist drills, in combination, a rotary grinding wheel having a rim with a flat circular surface and a beveled surface forming a circular edge; a base carrying said grinding wheel for rotation around a fixed axis; a turnable support member having an edge portion and being mounted in said base for turning movement in a plane perpendicular to said axis and in close proximity to said flat circular surface of said grinding wheel from a position in which said edge portion projects beyond said circular edge of said grinding wheel to a position in which a point of said edge portion coincides with said circular edge of said grinding wheel; and spring means interposed between said base and said turnable support member for resiliently counteracting said movement of said turnable support member towards said axis so that a twist drill held against the edge of the grinding wheel is resiliently supported by said edge portion of said movable support member engaging a flank of a flute of the drill near the tip thereof.

2. In an apparatus for grinding twist drills, in combination, a rotary grinding wheel having a rim with a flat circular surface and a beveled surface forming a circular edge; a base carrying said grinding wheel for rotation around a fixed axis; a turnable support member having a beveled edge portion and being mounted in said base for turning movement in a plane perpendicular to said axis and in close proximity to said flat circular surface of said grinding wheel from a position in which said beveled edge portion projects beyond said circular edge of said grinding wheel to a position in which a point of said edge portion coincides with said circular edge of said grinding wheel; and spring means interposed between the said base and said turnable support member for resiliently counteracting said movement of said turnable support member towards said axis so that a twist drill held against the edge of the grinding wheel for

grinding a web portion at the point of the drill is resiliently supported by said beveled edge portion of said movable support member engaging a flank of a flute of the drill near the tip thereof.

- 5 3. In an apparatus for grinding twist drills, in combination, a rotary grinding wheel having a rim with a flat circular surface and a beveled surface forming a circular edge; a base carrying said grinding wheel for rotation around a fixed axis; a turnable support member having an edge portion and being mounted in said base for turning movement in a plane perpendicular to said axis and in close proximity to said flat circular surface of said grinding wheel from a position in which said edge portion projects beyond said circular edge of said grinding wheel to a position in which a point of said edge portion coincides with said circular edge of said grinding wheel, said edge portion having a flat surface on the side facing said flat surface of said grinding wheel and having on the other side a bevel surface extending at a selected angle to said flat surface thereof; and spring means interposed between said base and said turnable support member for resiliently counteracting said movement of said turnable support member towards said axis so that a twist drill held against the edge of the grinding wheel for grinding the web portion at the point of the drill is resiliently supported by said bevel surface of said edge portion of said movable support member engaging a flank of a flute of the drill in contact with one cutting edge near the tip thereof.
- 10 4. In an apparatus for grinding twist drills, in combination, a rotary grinding wheel having a rim with a flat circular surface and a beveled surface forming a circular edge; a base carrying said grinding wheel for rotation around a fixed axis; an elongated support member having an edge portion and being mounted in said base for turning movement about a pivot point intermediate its ends in a plane perpendicular to said axis and in close proximity to said flat circular surface of said grinding wheel from a position in which said edge portion projects beyond said circular edge of said grinding wheel to a position in which a point of said edge portion coincides with said circular edge of said grinding wheel; pivot means in said base for turnably supporting said support member at said pivot point; and spring means interposed between said base and a point of said turnable support member spaced from said pivot point opposite to said edge portion for resiliently counteracting said movement of said turnable support member towards said axis so that a twist drill held against the edge of the grinding wheel for grinding the web portion at the point of the drill is resiliently supported by said edge portion of said movable support member engaging a flank of a flute of the drill near the tip thereof.
